DESIGN FOR AN ELEVATOR LANDING BUTTON FACEPLATE

Morrison John Brounn, Flushing, and Charles Michael Andres, Yonkers, N. Y., assignors to Otis Elevator Company, New York, N. Y., a corporation of New Jersey

Application January 8, 1949, Serial No. 150

Term of patent 14 years

(Cl. D72—1)

To all whom it may concern:

Be it known that we, Morrison John Brounn, a citizen of the United States and a resident of Flushing, county of Queens, State of New York, and Charles Michael Andres, a citizen of the United States and a resident of Yonkers, county of Westchester, State of New York, have invented a new, original, and ornamental Design for Elevator Landing Button Faceplate, of which the following is a specification, reference being had to the accompanying drawing, forming part thereof.

In the drawing:

Figure 1 is a view in perspective of an elevator landing button faceplate showing our new design; and

Figure 2 is a view in section taken along the line 2—2 of Figure 1.

What is claimed is:

The ornamental design for an elevator landing button faceplate, substantially as shown.

MORRISON JOHN BROUNN.
CHARLES MICHAEL ANDRES.
